UNITED STATES PATENT OFFICE.

WILLIAM F. BARKER, OF SOMERVILLE, MASSACHUSETTS.

SWIVEL-TIP FOR ELECTRIC CONDUCTORS.

No. 845,288.

Specification of Letters Patent.

Patented Feb. 26, 1907.

Application filed April 17, 1906. Serial No. 312,095.

To all whom it may concern:

Be it known that I, WILLIAM F. BARKER, a citizen of the United States, and a resident of Somerville, in the county of Middlesex and State of Massachusetts, have invented an Improvement in Swivel-Tips for Electric Conductors, of which the following description, in connection with the accompanying drawings, is a specification, like letters on the drawings representing like parts.

This invention has for its object the production of a novel and efficient swivel-tip for electric conductors, and while applicable for various purposes it is particularly useful in connection with flexible telephone-cords, the tips of which are held firmly in suitable binding-posts or holders.

It is necessary that the wire or wires forming the conductor and protected by braided or other insulation shall have a perfect electrical connection with the tip, and in many instances the twisting or bending of the conductor is apt to dislodge or break the tip or injure the binding post or screw.

The cords, which are in practice insulated conductors used in telephone practice to connect the receiver and the transmitter with the main circuit, are, as is well known, subject to rather rough usage in handling the instrument, and the cords are frequently twisted or turned in such a manner that the tip is broken or its electrical connection with the conductor damaged.

By my present invention the tip and the conductor are united by a swivel connection in a very simple yet efficient manner, so that any relative twisting of the tip and the conductor will not in any degree whatever injure the electrical connection between such parts. The tip remains tightly held in the binding-post and the conductor may be twisted or turned at will without loosening the hold or without any danger of breaking the tip.

The novel features of my invention will be fully described in the subjoined specification and particularly pointed out in the following claims.

Figure 1 is a view in elevation of a swivel-top embodying my invention connected with the conductor. Fig. 2 is an enlarged longitudinal sectional view thereof, the tip being shown in elevation. Fig. 3 is a detached view of the tip and the holder therefor in which the tip is free to rotate.

The electric conductor 1, which may be a single wire or a bunch or group of wires, is of usual construction covered with an insulating jacket or cover 2, which in the case of telephone-cords is usually a seamless braided fabric. A tubular shell or ferrule 3 is open at one end to receive the insulated conductor with a tight fit, the conductor in practice being forced into the open end of the shell, the other end 4 of the latter having a central aperture 5, Fig. 2. Through this aperture loosely extends the end of the tip 6, which in practice is a rod of metal of good conducting properties, the projecting end of the tip being adapted to be held by a binding post or screw or to enter a socket. At its inner end the tip is slightly enlarged to form a head 7, and the headed end is rotatably mounted in a metallic holder 8, the holder being preferably slightly tapered, as shown, to prevent any material longitudinal movement of the tip therein, while permitting free rotation of said tip.

The larger end of the holder is overturned at 9, Fig. 2, to retain the head of the tip in place. It will be seen from the drawings that the holder when inserted in the shell or ferrule 3 is considerably shorter than such shell, the smaller end of the holder in practice abutting against the closed end of the shell.

In assembling the parts the insulation is removed from the end of the cord to expose the conductor, as at 10, Fig. 2, and the bared part is wrapped around the holder 8 and soldered or otherwise firmly affixed thereto to make a good electrical connection. The holder and tip are then inserted in the open end of the shell and pushed in until the tip projects through the aperture 5, the end of the holder abutting against the closed end of the shell, as in Fig. 2, and the end of the conductor is forced firmly and securely into the shell behind the holder, so that when the assembling is complete the holder is cramped or held fast in the shell. The tip is free to turn or rotate relatively to the holder and shell, as will be manifest, and as the latter parts are fast with relation to the conductor or cord the latter can be turned or twisted indefinitely while the tip remains fixed. A swivel connection is thus provided by the holder between the tip and the conductor, so that no twisting, bending, or turning of the latter will affect the former, and the electrical connection always remains intact, as some portion of

the tip is always in contact with the holder under all circumstances and is thoroughly protected by the inclosing shell.

Having described my invention, what I claim as new, and desire to secure by Letters Patent, is—

1. The combination with a tip adapted to be inserted in a binding-post or the like, of a holder in which the tip is rotatably mounted and held from longitudinal movement, and a shell to receive the tip and its holder and having an opening at one end to permit the tip to project therethrough, the conductor being electrically connected with the holder within the shell.

2. The combination with a metallic holder and a tip, the latter being rotatably held in the former and extending beyond the same at one end, of a tubular shell to receive the holder and the end of the conductor, one end of the shell having an aperture through which the extended end of the tip projects, the conductor being electrically connected with the holder within the shell.

3. The combination with a tubular shell 25 having an aperture in its closed end, of a tip extending loosely through the aperture, an electric conductor inserted and fixedly held in the opposite open end of the shell, and a swivel connection between the tip and said 30 conductor, inclosed within the shell.

4. The combination with a tubular shell or ferrule having an aperture in its closed end, of a tip, extended loosely through the aperture, an electric conductor inserted and fixedly held in the opposite open end of the shell, and a non-rotatable holder for and in which the inner end of the tip is rotatably mounted, said holder being electrically connected with the conductor within the shell.

In testimony whereof I have signed my name to this specification in the presence of two subscribing witnesses.

WILLIAM F. BARKER.
